FIREMAN'S PROTECTOR

Francis J. de Javannes, New York, N. Y.

Application January 24, 1935, Serial No. 3,221

3 Claims. (Cl. 2—81)

My present invention relates to safety devices, and more particularly to an improved fire fighting device for firemen and the like.

It is well known that in fighting fires it is essential that the firemen get in close to the fire, if the fire is to be fought successfully. In order to attain such an advantageous position it is necessary for the fireman in a great many instances to move actually into the outskirts of the blaze, with the result that a great many firemen are injured and even killed by the inhaling of flames. Various expedients have been suggested for enabling firemen to reach a position with respect to a fire where they will be able to fight the fire to the best advantage, and yet which will prevent accidents happening to the firemen because of their proximity to the flame. As far as I am aware, none of these various expedients have been successful.

20 In my present invention I have designed a type of safety device for firemen and the like, which may be readily and comfortably worn by a fireman in the discharge of his duty, and which will not hamper his movements in the least, and further which when equipped to discharge a gas in accordance with my invention, will practically surround the fireman with an envelope of not only a non-inflammable gas but a gas which will not support combustion and will in itself aid in extinguishing the fire.

25 My device is preferably in the form of a poncho and in which the material is hollow and flexible, and preferably made of a flexible, resilient material, such as rubber, and the surface of which is provided with a plurality of perforations extending into the interior of the hollow member. Further I provide means for connecting the interior to a source of supply of non-flammable, non-combustion supporting gas, such for example as the usual 30 and ordinary commercial CO₂. My improved device is so arranged, that although the gas employed is heavier than ordinary air and therefore sinks downwardly, the shoulder portions of my poncho-shaped member are provided with perforations through which necessarily the gas under pressure is forced upwardly and thus practically surrounding the major portion of the head of the wearer with an envelope of non-combustion supporting gas, but which however, will not prevent 35 normal respiration of the person wearing the device. This is essential, as of course a heavy fire-fighting gas will not only not support combustion but also will not support respiration.

40 45 50 55 My device has the further advantage that in

case of accident the poncho-shaped element may be utilized as an emergency cot or stretcher.

In the accompanying drawing,

Fig. 1 is a perspective view of my improved device shown in position for wear on the figure of a fireman.

Fig. 2 is a vertical sectional side elevation of my improved device and

Fig. 3 is a developed plan view of the device.

Referring to the drawing, and particularly to Figs. 2 and 3, there is shown a device comprised of a front or top plate 10 and a rear or bottom plate 11 of flexible, resilient material, such for example as rubber. Such members 10 and 11 are substantially rectangular in shape, as shown in Fig. 3, and are connected together along their peripheral edges to thereby form a double faced hollow rectangular poncho-shaped member.

At one end of the members 10 and 11 there is formed, and preferably of the material of the members 10 and 11, an inlet nozzle 12 and at the other end there is formed a corresponding inlet nozzle 13.

Substantially midway along the length of the members 10 and 11 is formed an oval opening 14 made by cutting away the material of the members 10 and 11 and the peripheral edges of the opening just formed are joined together as shown in Fig. 2 to maintain the space between the members 10 and 11 in substantial air-tight condition. Perforations 15 are formed in either or both of the outer or inner rectangular members 11.

The resulting structure above described, and illustrated in Figs. 2 and 3, being of flexible, resilient material, the same may be placed in wearing position on a fireman 16, for example, by having such fireman insert his head through the opening 14. When thus placed in position on the fireman, the ends of the rectangular members 10 and 11 hang downwardly, one end in front of the fireman and the other end in the rear. The width of the members 10 and 11 is such that the combined widths of the two ends of the members 10 and 11 is but slightly less than the waist measurement of the fireman so that the fireman is practically enclosed in the device.

The space between the members 10 and 11 may be supplied with an inert gas, such for example as carbon dioxide, from a tank 17 which may be carried by an attendant, or from a source of supply mounted on the pumping engine, from which also leads the fire hose 18. The conduit or pipe through which the carbon dioxide gas is fed from the above referred to pumping engine passes through the pipe 19 and through a pressure reg-

ulating valve 20 into and through the nozzles 12 and 13. The pressure regulating valves 20 in the illustration of the device as shown are formed integral with a Y, one leg 22 of which is connected to the nozzle 12 by clamp 23 and the other leg 24 of which is connected to one end of a pipe 25, the other end of this pipe being supplied with a nipple 26 which is connected to the nozzle 13 by the clamp 27.

10 With the device constructed as above described, and worn in the position illustrated in Fig. 1, and assuming the device is ready for use and the fireman in position where the same is required, the fireman by manipulating the pressure-regulating valves 20, allows air to flow through the pressure-regulating valves 20 into the space between the rectangular members 10 and 11, and the gas, after reaching a certain pressure will flow out of the perforations 15 into 15 the atmosphere. The CO₂ or similar gas being heavier than the air will have a tendency to sink gradually and thus aid in extinguishing any flame which may be in the immediate vicinity thereof. Also because of the fact that the gas is 20 under pressure the same will flow through those perforations 15 on the shoulder portions of the device as shown in Fig. 1 and will be projected upwardly above the head of the fireman 16. The result is that the fireman is enveloped in 25 a shield of CO₂ and is thus protected from danger of burning or the like. The tank 17 may be carried by an attendant or may be of small enough size to be strapped on the back or shoulders of the fireman himself.

30 35 What I claim is:

1. In a device of the kind described, the combination of a hollow garment, substantially rec-

tangular in form and provided with a centrally located transversely extending orifice through which may be passed the head of the wearer in the surface of the garment, a plurality of perforations in one face of the garment communicating with the interior of the garment, means for supplying an inert gas under pressure to the interior of the garment for egress through the perforations, and means for regulating the pressure of the inert gas.

2. In a device of the kind described the combination of a hollow, substantially rectangular and elongated member comprised of front and back plates of flexible, resilient material secured together about the peripheral edges thereof, 15 inlet passages at opposite ends of the member, perforations through the members extending into the space between said members, and means for supplying an inert gas under pressure to the interior of the device and for egress through the 20 perforations.

3. In a device of the kind described, the combination of a hollow garment substantially rectangular in form, an orifice centrally located with respect to the surface dimensions of the 25 garment and extending transversely therethrough and through which may be passed the head of the wearer to position the garment to shield the front and back of the wearer, a plurality of perforations in the outer exposed face of 30 the garment, when the same is in position on the wearer, said perforations communicating with the interior of the garment, and means for supplying inert gas to each end of the hollow garment simultaneously for egress through the perforations.

FRANCIS J. DE JAVANNES.
